UNITED STATES PATENT OFFICE.

SAMUEL W. DIXON, OF FINDLAY, OHIO, ASSIGNOR OF ONE-HALF TO
THORNTON F. MORRISON, OF SAME PLACE.

KILN FOR POTTERY, &c.

SPECIFICATION forming part of Letters Patent No. 339,535, dated April 6, 1886.

Application filed January 16, 1886. Serial No. 188,776. (No model.)

To all whom it may concern:

Be it known that I, SAMUEL W. DIXON, a citizen of the United States, residing at Findlay, in the county of Hancock and State of Ohio, have invented certain new and useful Improvements in Kilns for Pottery, &c.; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of a vertical section taken through the flues I. Fig. 2 is a sectional plan of the floor. Fig. 3 is a vertical section taken through the flues H. Fig. 4 is a sectional plan showing the construction of the circular flues. Fig. 5 is a front elevation of the kiln complete, and Fig. 6 is a sectional plan showing the construction of the floor S.

This invention relates to improvements in brick and tile kilns; and it consists in the construction and novel combination of parts, as hereinafter set forth, and pointed out in the claims.

In the accompanying drawings, G represents the base of the kiln.

V is the support or shoulder for the floor S, hereinafter described, to rest upon.

E are the fire-boxes, equally distant apart, and provided with proper grates, and have the ash-pits Z under them.

H H represent the chimneys on the inside of the kiln, having the sliding gates A near their lower ends, and the sliding gates B near their tops, and communicating with the fire-boxes E by the passages A', as shown.

I I are four vertical chimneys on the outside of the kiln, and controlled by the valves or sliding gates C.

N N are the equidistant chimneys, which rise from the kiln around the edge of dome, and are provided with the sliding gates O.

N' is a chimney rising from the center of the dome, and provided with the sliding gate O', as shown.

R R are four radial equidistant walls within the kiln upon its base. The purpose of the walls R is to divide the downdraft currents of

air and keep the said drafts separate from each other.

F F are four horizontal flues running from the lower ends of the chimneys I to the center of the base of the kiln, where the walls of the flues unite.

L L are concentric circular flues at the base of the kiln, and M M are straight flues surrounded by the former. The flues L and M open into the large flues F.

X X are upright bricks in the walls of the flues L M, and W W are openings in said walls.

J is the door of the kiln, situated in any convenient position.

T T are chimneys, made of green or unburned tiles, which rest on the floor S, as shown, under the chimneys N N', and are replaced every time the kiln is filled for burning. Each chimney T is between and equally distant from two chimneys, H.

D D are four iron bands, preferably four inches wide, three-sixteenth inch thick, and placed thirteen inches apart, one at the top of kiln, one above the door J, one in the center between the two, and one eighteen inches below the top of door. These bands support the kiln.

K K are ventilating holes in the roof of the dome.

S is the reticulated floor of the kiln, which, when in place, rests with its rim upon the circular shoulder V.

Y is the foundation upon which the floor and the bricks or tiles that make the flues L and M rest.

P P are tiles, preferably about four by eight inches, and twenty-two inches long, which rest over the four flues F, the walls of the flues L M resting on the tiles, as shown. The floor S is of general circular shape, and is composed at its central portion of the straight bars s', crossing each other at right angles and outside of the central portion of the radial bars s² and curved bars s³. Its edge has the notches or recesses s⁴ for the accommodation of the flues H, as shown.

To cause an updraft through the kiln, close the sliding gates B and C and open the gates A, O, and O'. The draft will then be from the fire-boxes E into the flue H, and thence through the flues L and M and up the chim-

neys T N N'. This causes both center and side updraft. If a side draft only is wanted, the sliding gate O' of the central chimney, N', is closed. If a center draft only is wanted, the 5 gates O of the side chimneys, N, are closed.

To create a downdraft in the kiln, close the gates A, O, and O', and open the gates B and C. The draft is now from the fire-boxes E into and up through the flues H, and thence down 10 through the tile in kiln into the flues L and M, thence into the flues F, and up the chimneys I. In the first case the firing begins at the bottom, and in the second case it begins at the top. When the draft is too strong in any direction, 15 the sliding gates can be partially closed, so as to regulate the same.

A kiln may be arranged to have a down-draft only by omitting the chimneys N, N', and T and the sliding gates B in the chimneys 20 H. The draft will then pass up said chimneys and descend thence, pass under the reticulated floor, and go up the chimneys I.

A kiln may be arranged for one updraft only by omitting the chimneys I and the sliding 25 gates B in the chimneys H. The draft will then be down the chimneys H, under the floor, and up through the chimneys T N N'. These, however, are but modifications of the kiln, having both up and down drafts, as described.

30 A kiln may be arranged with four, five, six, seven, or more fire-boxes, E, and with as many chimneys, H, T, and N. A kiln fifteen feet in diameter should have four fire-boxes. A kiln eighteen feet in diameter should have five fire-boxes. A kiln twenty feet in diameter should have six fire-boxes. A kiln twenty-two feet in diameter should have seven

fire-boxes, and so on as the size of the kiln is increased.

Having described this invention, what I 40 claim, and desire to secure by Letters Patent, is—

1. In a kiln, the combination of the oven or body, the reticulated detachable floor S of the fire-boxes, the inside vertical flues, H, communicating with said fire-boxes and having the sliding gates A B, the outside chimneys, I, having the sliding gates C, the flues F, and flues L and M, communicating with the flues F, substantially as specified. 50

2. In a kiln, the combination, with the oven or body, the reticulated floor S, the fire-boxes, and the flues L and M below the same, and constructed substantially as described, of the chimneys I N N', respectively provided with 55 the gates C O O', the flues H, provided with the gates A B, and the temporary flues T, made of unbaked or green tiles, substantially as specified.

3. In a kiln having fire-boxes E, the combination of the oven-body, the reticulated floor S, and the flues L and M below the same, with the chimneys I N N', respectively provided with the gates C O O', the flues H, provided with the gates A B, and the temporary flues 65 T, made of unbaked tiles, substantially as specified.

In testimony whereof I affix my signature in presence of two witnesses.

SAMUEL W. DIXON.
